US00D887514S

(12) **United States Design Patent** (10) **Patent No.:** **US D887,514 S**
(45) **Date of Patent:** **** Jun. 16, 2020**

(54) **FLOATER PADDLE**

(71) Applicant: **Danilo P. Gerona**, McKinney, TX (US)

AU 658998 B2 5/1995
EP 1498159 A1 1/2005

(72) Inventor: **Danilo P. Gerona**, McKinney, TX (US)

(Continued)

(**) Term: **15 Years**

(21) Appl. No.: **29/716,579**

(22) Filed: **Dec. 10, 2019**
